(57) **CLAIM**

The ornamental design for cedar lined suspended shelving, as shown and described.

DESCRIPTION

FIG. 1 is an isometric view of cedar lined suspended shelving showing a first embodiment of my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof;

FIG. 8 is an isometric view of the cedar lined suspended shelving in its collapsed state;

FIG. 9 is isometric view of cedar lined suspended shelving showing a second embodiment of my new design;

FIG. 10 is a front view thereof;

FIG. 11 is a rear view thereof;

FIG. 12 is a right side view thereof;

FIG. 13 is a left side view thereof;

FIG. 14 is a top view thereof;

FIG. 15 is a bottom view thereof; and,

FIG. 16 is an isometric view of the cedar lined suspended shelving in its collapsed state.
